(57) CLAIM

The ornamental design for a soap pump, as shown and described.

DESCRIPTION

FIG. 1 is a perspective view of a soap pump embodying this invention, with a phantom view of a base for the pump;

FIG. 2 is a top view of the pump shown in FIG. 1;

FIG. 3 is a front view of the pump shown in FIG. 1, with a phantom view of a base for the pump;

FIG. 4 is a right side view of the of the pump shown in FIG. 1, with a phantom view of a base for the pump;

FIG. 5 is a rear view of the pump shown in FIG. 1, with a phantom view of a base for the pump; and,

FIG. 6 is a left side view of the pump shown in FIG. 1, with a phantom view of a base for the pump therefor.

The phantom lines in the Figures are for illustrative purposes only and form no part of the claimed design.
